(57) **CLAIM**

The ornamental design for a high efficiency hub for pressure jet helicopters, as shown and described.

DESCRIPTION

FIG. 1 is a perspective view of a high efficiency hub for pressure jet helicopters showing the new design;

FIG. 2 is a side view thereof;

FIG. 3 is a end view thereof;

FIG. 4 is a top view thereof; and,

FIG. 5 is a bottom end view thereof.

The broken lines shown in the drawings represent portions of the high efficiency hub for pressure jet helicopters that form no part of the claimed design.
